UNITED STATES PATENT OFFICE.

HENRY E. WAITE, OF NEW YORK, N. Y.

GALVANIC BATTERY.

SPECIFICATION forming part of Letters Patent No. 374,329, dated December 6, 1887.

Application filed May 5, 1886. Serial No. 201,223. (No model.)

To all whom it may concern:

Be it known that I, HENRY E. WAITE, a citizen of the United States, and a resident of the city, county, and State of New York, have invented a new and useful Improvement in Galvanic Batteries, of which the following is a specification.

My invention relates to galvanic batteries for medical purposes, and has for its object to improve the construction and arrangement of such batteries, whereby they may be more conveniently handled in use or in carrying from place to place.

To these ends my invention consists in the improved construction and arrangements of parts, substantially as hereinafter pointed out.

Referring to the accompanying drawings, forming part of this specification, Figure 1 is a perspective of the battery closed. Fig. 2 is a side view of the battery opened. Fig. 3 is a transverse section on line 1 2, Fig. 2. Fig. 4 is a perspective of the battery-cell, tray removed. Fig. 5 shows the battery-tray platform. Figs. 6 and 7 are details.

The box or case A may be of any suitable shape or size to meet the requirements of any particular battery, and it may be of any suitable material, though I prefer to make it of wood. The top B is preferably hinged to the rear side and suitably secured to the other sides and provided with a handle for convenience in carrying the battery.

The front C of the box or cabinet is made to open either from the center, as indicated in Fig. 1, or the side is hinged to one end, as shown in Fig. 2.

Upon a suitable platform or partition, D, supported near the upper part of the box or case, are arranged the plates or electrodes for the battery, each being connected to the under side of the platform D and held in position by the screw-pins d', the upper ends of which form the terminals for conveniently connecting up the various battery-cells for use. Also arranged upon said platform D are the desired switches or commutators E and the binding screws + and -, one of which is connected to the last plate of the extreme battery-cell and the other is connected to the cord and plug F, so that any desired number of battery-cells may be easily included in the circuit between the binding-posts.

Supported slightly above the bottom of the case is the platform or shelf G, having a rod or rods, H, connected therewith and extending up through the platform D. These rods H are provided with screw-threaded ends h, entering the shelf G or a projection connected therewith, and there may be one rod attached to the middle, as shown in dotted lines in Fig. 5, or one at each end. Upon this shelf or platform G rests the battery-box I, containing the desired number of cells; and it will be seen that the box and contained cells can readily be removed or drawn out for filling or examining them. A hydrostat or cover, J, for the cells is provided with a proper packing, j, of rubber or other suitable material, to seal the jars or cells when desired, and the rear and front of the case are provided with grooves or recesses K K, into which the side edges of the hydrostat fit when in position above the cells, and when the battery is in operation the hydrostat is removed from its position above the cells and placed in the recess below the platform G for convenience of storage. When the battery is to be transported, the hydrostat-plate J is placed over the cells with its rubber packing next to the jars and its edges fitting into the recesses K in the sides of the box, and the handles or rods H are screwed down until the platform G is lifted up and tightly presses the cells against the under side of the hydrostat, and they are thereby effectually sealed and the battery is ready for handling. When the battery is to be used, the rods are unscrewed, so as to allow the platform G to resume its normal position, when the hydrostat J is removed from above the cells and placed in the recess under the platform G. The battery may then be removed for filling or examination, if desired. If it is in proper condition, the rod or rods H are raised until the electrodes are properly immersed in the liquid in the cells, when the rods H are turned so that the pins h' rest crosswise on the plates P secured to the side of the platform D, and the battery is thus held in operative condition.

Any form of switches and electrodes may be used for applying the electricity, and in Fig. 7 I have shown one convenient way for arranging the ordinary hand or sponge electrode. In making said electrode a screw, a, is soldered to a plate, b, of copper or other

suitable metal, and the plate is then spun or otherwise formed into the desired shape, preferably similar to that shown in Fig. 7, and the sponge or other covering material can be readily secured by tying or otherwise, and the screw not only holds the electrode in its handle, but furnishes a good conducting medium. From this it will be seen that my improved battery is very convenient and compact, and is well adapted for the purpose for which it was intended, while the construction is simple, cheap, and durable.

What I claim is—

1. In a battery, the combination, with the case, of a platform supporting the removable battery-tray containing the cells and handles attached to the platform for raising it, substantially as described.

2. In a battery, the combination, with the case, of a platform elevated above the bottom of the case, a battery-tray supported upon the platform, a removable hydrostat arranged above the tray, and a recess under the plat-

form to receive the hydrostat, substantially as described.

3. The combination, with a case provided with recesses, of the platform, the tray carried thereby and containing the cells, the hydrostat adapted to enter the recesses, and means for elevating the cells against the hydrostat, substantially as described.

4. The combination, with the battery-plates, of a platform carrying the battery-tray, a removable hydrostat, and lifting handles attached to the tray and adjustably connected therewith, whereby the tray may be lifted into contact with the hydrostat or with the plates and supported in either position, substantially as described.

In testimony whereof I have signed my name to this specification in the presence of two subscribing witnesses.

HENRY E. WAITE.

Witnesses:
